UNITED STATES PATENT OFFICE.

WRAY FALWELL, OF FITCHBURG, MASSACHUSETTS.

VACUUM FUEL-FEED SYSTEM FOR MOTOR-VEHICLES.

1,299,443.

Specification of Letters Patent.

Patented Apr. 8, 1919.

Application filed June 23, 1915. Serial No. 35,955.

To all whom it may concern:

Be it known that I, WRAY FALWELL, a citizen of the United States, residing at Fitchburg, in the county of Worcester and State of Massachusetts, have invented certain new and useful Improvements in Vacuum Fuel-Feed Systems for Motor-Vehicles, of which the following is a specification.

The invention has for an object to give an improvement in fuel supply systems of internal combustion engines in which the vacuous condition produced in the inlet connections of the usual type of such engines is utilized to carry fuel from a main storage tank at a low level to an auxiliary tank at a high level, from which the fuel may readily pass by gravity to the engine or the charge forming device. It is an important aim to provide a device of this type specially suitable for use in motor vehicles. Another important aim is to enable the construction of the device so as to operate with a single auxiliary chamber or tank. Another important object is to simplify the construction and connections of valves by which communication with the engine or other vacuum producing means, the main supply tank, carburetor and atmosphere are controlled. A further purpose is to give an improved float action. Another purpose is to give a specific improvement in tandem valve construction by which two valves on a common stem seating in the same direction will operate positively and differences in wear will be compensated for automatically.

Additional objects, advantages and features of invention will appear from the construction, arrangement and combination of parts, constituting one embodiment of my invention as hereinafter set forth and more particularly shown in the drawings, where,

Figure 1 is a diagrammatic view of a motor vehicle equipped with my invention,

Fig. 2 is an enlarged vertical sectional view of my auxiliary tank,

Fig. 3 is a fragmentary vertical section at right angles to Fig. 2,

Fig. 4 is a top view of the device.

Fig. 5 is a cross section on the line 5—5 of Fig. 2,

Fig. 6 is a detail of the safety check valve,

Fig. 7 is a detail of a fuel cut-off to the auxiliary tank.

There is illustrated a motor vehicle 10 of familiar construction having an internal combustion motor 11 in the forward part

thereof to which leads the usual inlet manifold 12 connected to a carburetor 13, and at the back end of the vehicle a main fuel tank 14 is mounted. Immediately to the rear of 60 the motor a dashboard 15 is located, upon the upper part of which within the hood 16 over the motor there is located my auxiliary tank 17. This comprises a simple cylindrical or otherwise shaped receptacle 17 which in 65 the present case is represented as a brass casting with integral attaching lugs 18 adapted to set against a flat surface and being apertured for the reception of mounting screws or bolts. The receptacle is 70 formed with a drain or outlet extension 19 having an enlarged bore 20 in its outer part and a reduced threaded opening 21 therefrom in which there is engaged a screw valve seat 22. The outer part of the bore is 75 threaded and formed with a peripheral rabbet 23. Engaged snugly on this rabbet there is a small swivel chamber fitting 24, having an opening 25 in its outer part of the same diameter as and aligned with the bore 20, 80 through which there is slidably inserted a hollow bolt 24' engaged in the threaded bore 20, by which the swivel chamber fitting 24 is held to a close union with the outlet extension. A drain cock 26 is engaged in the 85 end of the bolt, and a suitable strainer 27 of cylindrical form is fixed in the bolt, the passage through which is enlarged immediately of the strainer, and ports 28 formed in the bolt, communicating with the interior 90 of the chamber 24. The chamber is formed with a boss 29 at one side tapped and fitted with a customary union 30, by which connection is made with the gravity supply pipe 31 leading to the carburetor, this pipe having a helical coil 32 therein for a purpose to 95 be described.

The auxiliary tank is formed with a rest 33 intermediately of its height, which in the present case consists of a flange having a flat 100 upper side, extending around the tank. The tank is formed with a thickened upper edge portion 34, drilled and tapped to receive fastening screws 35 by which a top plate 36 is secured upon the tank, and by which it is 105 hermetically closed.

At one side of the plate 36 a boss 37 is formed, having a central inlet opening 38 therethrough tapped at its outside part to receive the hollow bolt 39 under which the 110 carrying flange 40 of a basket strainer 41 is secured, resting upon a shoulder 42 for that

purpose. The boss is formed with a peripheral rabbet in which there is seated a swivel member 43, the upper part of which has a close fit against the head of the bolt 39, which also has lateral ports therein communicating with the annular space 45 between the bolt and the swivel member. By means of the familiar union 46 connection is made with the supply pipe 47 from the tank 14 through the boss 48 formed on the side of the swivel member 43.

A second boss 49 is formed on the plate 36 at its upper side and a corresponding boss 49' is formed thereunder on the lower side 15 of the plate, a circular recess 50 being formed in the upper boss, centrally of which a threaded opening 51 is formed, in which there is engaged a bolt 52 by which a swivel connection 53 is held snugly against the boss, 20 having a passage therein alined with the recess 50 and having a lateral outlet 54 in which there is engaged a union 55 connected to the vacuum pipe 56, which leads to the manifold 12 and is connected thereto by a 25 similar union 57 engaged in a cap opening made for the purpose in the manifold.

An integral cylindrical body 58 is formed on the upper side of the plate 36 concentric with the seat in the screw seat 22 in the bottom of the tank 17, having a concentric bored passage 59 therethrough at opposite ends of which seat members 60 are threaded in the body, having opposed seats on their inner sides. A cored by-pass duct 61 is formed 35 in the body opening at one end on the inner face of the plate 36 beside the inner seat 60, and at its outer end opening into the passage 59 immediately within the outer seat 60. The outer end of the body 58 is formed 40 with an enlarged circular recess 62 concentric with the passage 59 and closed by a cap 63 threaded in the outer part of the recess. Opening into the recess 62 beside the outer seat 60 there is a cored duct 64 leading 45 downwardly in the body 58 beside the passage 59, and then laterally to the recess 50, by which communication is established with the manifold. Vent ducts 67 open from the passage 59 horizontally at the base of the 50 body 58.

A three-valve stem 65 is engaged slidably through the seats 60 from the tank 17, a cylindrical double valve body 66 being engaged thereon fitting snugly and slidably 55 in the passage 59 between the seats 60. This valve is shaped at each end for alternative seating upon the seats 60, so that each end constitutes a valve. It has sufficient movement to fall well below the upper or outer 60 end of the duct 61 when at the lower limit of its movement, and likewise clear the opening of the vents 67 when at the upper limit of its movement. The stem 65 is of a size to give ample clearance therearound through 65 the seats 60. It extends to near the bottom

of the tank, where it is provided with a collar 68 just above its extremity, engaged reciprocably in a caging 69 carried at the upper side of a fuel valve 70, a light spring 71 being confined between the valve and collar, by which the valve is yieldably held at the outer and lower limit of its movement on the stem 65. In this position, under downward movement of the stem, it will seat a little before the valve 66 engages the lower 75 seat 60, when the spring 71 yields and permits the necessary further movement for seating of the valve 66 upon the lower seat 60. The valve 70 is formed with a needle extension 72 engaged through the seat 22, 80 which has a port therethrough of larger diameter, permitting proper flow of fuel when the valve is raised.

Two hangers 73 are formed on the under side of the plate 36 equally spaced diametrically from the stem 65, upon which short links 74 are pivoted, connected also to the stem 65 in such a way as to permit full movement thereof for alternate seating of the valve 66 on the seats 60. This means 90 that the connection would have to be loose enough to permit a slight degree of lost motion between the links 74 and stem 65. An annular float 75 is mounted in the tank 17 for free vertical movement therein, and 95 adapted to rest upon the rest 33 at the lower limit of its movement. At opposite sides thereof, in line with the hangers 73, upwardly extending links 76 are pivoted on top of the float, having longitudinal slots 100 77 in their upper end portions in which there are slid able transverse pins 78 to each of which are connected two links 78' extending inwardly and pivoted on respective sides of the adjacent hangers 73. There may be two 105 of the links 74 from each hanger to the stem 65, and these are connected to a pin 79 rigidly fixed through the stem 65 projecting some distance beyond the links, as do the pins 78. From each pin 78, two 110 springs 80 extend to the pin 79 one on each side of the links. These springs are under retractile tension, so that when the springs swing below the pivotal connection of the links with the hangers the springs will exert 115 a downward pull on the stem 65 by which the valve 70 will be seated, cutting off communication with the carbureter and communication with the vents at the top of the tank will be closed by the valve 66 engaging 120 the lower seat 60. At the same time the port in the upper seat is opened, forming communication between the tank and the intake of the motor, producing a partial vacuum, which is sufficient to draw fuel through the 125 pipe 47 from a considerably lower level.

With the parts connected as described, the pipe 47 being arranged to take fuel from the bottom of the tank 14, fuel being supplied and the motor in operation, when the 130

parts in the tank are in the position last mentioned a rapid flow of fuel from the tank 14 to the tank 17 will be caused. Rise of fuel in the tank 17 will lift the float, 5 which will rise for a short distance without moving the links 78', by reason of the free movement of the pin 78 in the slot 77, which comprises a lost motion connection. As soon as this pin engages the lower end of the slot 10 it will be lifted, raising the spring, and when the springs pass above the pivotal connection between the links and hangers the links 78' will first move to their upper limit of oscillation, which will cause the springs 15 to exert a strong upward pull on the valve stem 65. The springs and links 78' are limited in their springing movement by suitable lugs 81 formed on the hangers 73 a suitable distance above and below the links 20 78' for engagement therewith at the proper limits. Upon swinging upwardly the pins carried at the outer ends of the links 78' will stop short of the upper ends of the slots 77, for a purpose to appear. When the rod 25 65 is raised, it will be apparent that the communication with the intake of the motor will be cut off by engagement of the valve 66 with the upper seat 60. This movement will also be sufficient to unseat the valve 70, 30 and the vents being opened by the valve 66 in this position fuel will be free to pass to the carbureter.

As the fuel level is lowered in the tank the float will fall, moving downwardly a 35 short distance before the links 76 engage positively with the pins 78, and continued movement of the float will then draw the pins downwardly, moving the links 78' and the springs, which will soon pass below the pivot 40 centers on the hangers, snapping the links to their lowermost position and pulling downward on the stem 65 with the result before mentioned. The downward movement of the links 78' will be checked before the 45 pins 78 engage the lower ends of the slots 77, so that immediate riding of the float for a short distance will not raise the spring, and the tank will receive a considerable amount of fuel before the action of the device is 50 reversed.

If it is desired to guard against dangers from back fire in the motor and the possibility of an explosion in either of the tanks a small check valve 82 may be incorporated 55 in the recess 62 as shown in Fig. 6.

With the device as shown it is desirable to mount the tank 17 as high as possible above the main tank when used on motor vehicles in the relation shown in Fig. 1, in order to 60 minimize liability of the auxiliary tank siphoning full and wasting fuel. If desired, however, a positive closure of the fuel feed may be attained, as shown in Fig. 7, where connections and fittings correspond 65 ing to those previously described in the out-

let extension are engaged and fitted in the boss 37 with the exception of the basket strainer 41, the parts being inverted from the position first described, a screw seat 22^a being engaged in the passage 38, with the 70 seat presented downwardly. A small cage 83 is formed integrally on the under side of the plate 36 beneath the seat 22^a, including a plate 84 spaced below the seat and having a concentric opening therethrough. 75 Loosely and slidably engaged in this opening there is a long stem 85 of a small valve 86 normally resting by gravity on the plate 84 in disengaged position, the lower end of the stem being positioned to engage the upper side of the float just before it reaches the upper limit of its movement, whereby the valve will be seated, operating to prevent siphoning.

It is an advantage of the lost-motion connection between the float and valve control that liability of abrupt and repeated reversals of operation of the device is eliminated, which without this connection has been found to prevent proper action of devices of this kind at times under prior methods of construction. The construction set forth has been found to enable the use of a single reservoir auxiliary with very satisfactory results. The construction and 95 assemblage of the device are simple, inexpensive and durable, and the parts readily accessible for cleaning without liability of derangement.

While, in the use of the foregoing construction the fuel supply from the auxiliary tank is cut off during the time when fuel is being drawn thereinto, the time required for complete refilling of the auxiliary tank is so short that no detrimental effect is manifest in the operation of the motor, even at very high speeds, as the carbureter carries more than sufficient fuel to operate the engine for the very few seconds in which it has been found necessary for the fuel to be 100 cut off from the auxiliary tank. By providing the coils 32 the elasticity of the fuel ordinarily used allows a continued flow of fuel to the carbureter for a time after the valve 70 is seated.

In order to start the system after incorporation on a vehicle, if there is no fuel in the carbureter or other charge forming device used, it will be apparent that the parts are in position for filling of the auxiliary tank if the engine is operated, and it is found that a few turns of the motor by hand or starting device is sufficient to complete a cycle of action in the parts of the auxiliary tank supplying fuel to the charge forming 120 device, the throttle being closed in the ordinary way during this initial operation.

It is to be noted that in some of my claims valves and some of the connections therefor are only specified to control the 130

exhaust connection and the drain connection from the auxiliary tank. The reason for this is that by properly proportioning the exhaust and air vent passages or capacity, 5 no other valves are essential.

What is claimed:

1. In a device of the class described, an auxiliary tank having fuel inlet and outlet connections, air inlet and outlet connections, 10 the three connections last named including aligned valve seats, the seat of the air outlet being disposed oppositely to those of the other two connections, valves disposed for engagement with said seats, and a common 15 operating stem therefor, the air inlet and outlet valves being spaced for alternate seating, the air inlet and fuel outlet valves being normally spaced more than the respective corresponding seats, yielding connections 20 between said fuel outlet valve and said stem member, and a fuel controlled device operatively associated therewith for the purposes described.
2. In a device of the class described, a 25 valve controlling means comprising a tank, a central vertically reciprocable valve actuating member therein, fixed supports on the tank at the upper part at opposite sides of the reciprocable means, a float in the tank, 30 outwardly extending links on said supports, spring elements connected with the outer ends of the links and the reciprocable member, means to limit oscillation of the links, and lost motion connections between the 35 float and the outer ends of the links.
3. In a device of the class described, opposed valve seats, valves therefor, means connecting the valves in a relation for alternate seating engagement, a third seat, presented in the direction corresponding to that 40 of one of the first named seats, a third valve therefor, a lost motion connection between

the last named valve and said means connecting the first named valves, and a resilient element coengaged between said means and said third valve. 45

4. In a device of the class described, valve seats presented in a common direction, valves therefor, a common operating member for seating and unseating the valves, operatively associated therewith, a resilient connection being formed between one of the valves and said operating member, said one valve last named being positioned to seat in advance of the other valve, and the resilient 50 connection being in individual train between the valve and operating member, whereby the one valve may yield to pressure of its seat until the other is seated.

5. In a device of the class described, a 55 tank, a closure fitting therefor comprising a body having a valve passage therein communicating at one end with the interior of the tank and having duct connections at its other end, opposed seats at opposite ends of 60 the passage, a by-pass duct leading from an outer part of the passage inwardly of the outer seat and in communication with the tank, external duct connections with said passage outwardly of the outer seat, vent 65 connection with the passage outwardly of the inner seat, and a valve device reciprocable in the passage having portions to alternatively engage the outer seat on the one hand and the inner seat and the vent opening on the other, and fuel controlled means 70 to operate the valve device.

In testimony whereof I have affixed my signature in presence of two witnesses.

WRAY FALWELL.
